UNITED STATES PATENT OFFICE.

GEORGE W. FALLIN, OF MONTGOMERY, ALABAMA, ASSIGNOR TO MATHEW M. FREED, OF MONTGOMERY, ALABAMA.

SAD-IRON HEATER.

No. 901,797.

Specification of Letters Patent.

Patented Oct. 20, 1908.

Application filed May 13, 1908. Serial No. 432,680.

To all whom it may concern:

Be it known that I, GEORGE W. FALLIN, a citizen of the United States, and a resident of Montgomery, in the county of Montgomery and State of Alabama, have invented 5 certain new and useful Improvements in Sad-Iron Heaters, of which the following is a specification.

My invention is an improvement in sad 10 iron heaters, and consists in certain novel constructions and combinations of parts hereinafter described and claimed.

Referring to the drawings forming a part 15 hereof, Figure 1 is a perspective view of a sad iron provided with my improvement. Fig. 2 is a central longitudinal section. Fig. 3 is a section on the line 3—3 of Fig. 2, and Fig. 4 is a central longitudinal section through the plug.

20 The present embodiment of my invention consists of a body portion 1, comprising a casting of steel or iron, cored, and provided centrally with the air supply openings 2.

25 The main generator comprises a tube 3, having one end inserted in a plug 4, which plug is provided with an annular flange 5, and with a passage 6, communicating with the interior of the tube 3.

30 A tee 7 is inserted in the outer end of the plug, the tee being provided with a passage 8 communicating with the passage of the plug, and provided at the junction of the branch 9 and the main portion of the tee with a valve seat 10, which is adapted to be 35 closed by a needle valve 11, threaded into the end of the tee, and provided with a hand wheel 12.

40 The end of the tee 7 is closed by a packing nut 13, a packing 14 being arranged between the nut and the end of the tube.

The lateral branch 9 of the tee is provided with a passage 15 communicating with the passage 8, and also with the fuel tank 20.

45 The tube 3 is lined with asbestos 21, and communicates by another tube 22 with the lower generator 23, which is supported directly below the main generator or tube 3. The generator 23 is provided with a plurality of perforations 24, for permitting the escape of gas, the jets impinging against the surface of the main generator 3.

The free end of the main generator is

closed by a cap 25, and the fuel tank 20 is provided with an inlet opening 26, normally 55 closed by a screw threaded plug 27.

The bottom of the fuel tank is covered by a fine wire gauze 28, to prevent the passage of impurities into the tee.

In operation, the main generating tube 3 60 is heated by any suitable means until the alcohol therein is vaporized the vapor passing therefrom through the connecting tube 22, to the generator 23, and upon issuing from the perforations 24, the gas is lighted. 65 The jets thus continue the vaporization of the alcohol in the main generator, and the heat therefrom passing upwards impinges upon the inner surface of that face of the sad iron which is uppermost. When the 70 lower face of the sad iron in use becomes cool, the iron is reversed thus bringing the heated face in operative position.

The body of the sad iron is mounted in a yoke-shaped handle 30, one arm 31 of the 75 handle being provided with a bearing 32 engaged by the plug 4, and the other arm 32^a of the handle is connected with a boss 33 on the body by a screw 34. A spring actuated catch 35 is journaled on the arm 32^a as at 36, 80 and the free end thereof is provided with a pin 37 adapted to engage openings 38 whereby to fix the body with respect to the handle.

The arms 31, 32^a of the handle are connected by a bolt 39, and a plate 40 is arranged above the bolt extending between the arms. 85

It will be noticed that the generator 23 extends beyond the end of the tube 3, as at 41, adjacent to the end of the sad iron body, 90 whereby to heat the point of the arm by the direct impingement of the jets thereon instead of by diffusion.

The plug 27 is hollow as shown in Fig. 4, and is provided with an opening 42 in its upper face and an opening 43 in its lower face, to permit the ingress of air to take the place of the fuel passing to the generator. The object of the plug so arranged is to prevent the alcohol from being spilled while 100 manipulating the iron.

I claim:

The combination with the body of a sad iron, of a heater comprising a plug engaging the body having a longitudinal opening, a 105 tube threaded into the plug, and extending

into the body of the sad iron, a second tube arranged below the first tube and provided with a plurality of perforations, a tube connecting the two first named tubes and extending into the upper tube, an asbestos lining in the upper tube, a fuel tank connected with the plug, and a valve for con-

trolling the communication between the tank and the plug.

GEORGE W. FALLIN.
